UNITED STATES PATENT OFFICE.

GEORGE F. SCHEFFER, OF DETROIT, MICHIGAN.

TYPEWRITER.

Application filed November 19, 1921. Serial No. 516,341.

To all whom it may concern:

Be it known that I, GEORGE F. SCHEFFER, a citizen of the United States, residing at Detroit, in the county of Wayne and State 5 of Michigan, have invented certain new and useful Improvements in Typewriters, of which the following is a specification.

This invention relates to improvements in typewriters in which are employed a carriage 10 movable in forward and reverse directions, a combined platen and paper-feed roller carried by the carriage, mechanism for moving the carriage forward during the writing operation and mechanism adapted to 15 be operated to turn the paper-feed roller to the desired extent at the completion of each line of writing during the operation of the machine.

In machines of this character the carriage 20 is automatically moved forward during the writing operation and at the completion of each line of writing the carriage is manually returned or moved in the reverse direction; and during or immediately prior to the 25 return of the carriage and by substantially the same manual operation the mechanism for turning the paper-feed roller is actuated.

The carriage is located at the upper portion of the machine and the part which is 30 engaged by hand to move the carriage in the reverse direction and actuate the feed-roller turning mechanism is located in the vicinity of the carriage and above the key board of the machine and in such position 35 that the operator is required to raise the hand and arm a considerable distance above the normal position for operating the keys of the key board. The numerous times that this manual operation of the carriage of the 40 machine is fulfilled by the operator in the course of a comparatively short period of time causes a strain to be placed upon the arm and hand resulting not only in the fatigue caused thereby but also in the consumption of the time represented by the 45 many up and down movements of the hand and arm during a work period.

The object of my invention is to eliminate the time required for raising and lowering 50 the arm and hand for the carriage return operations and also to eliminate the fatigue resulting therefrom; and I accomplish my object by the provision of a novel, simple and efficient mechanism by means of which 55 the carriage may be returned and the paper feed-roller advanced after the completion

of the writing of each line by a horizontal movement of the hand across the front of the key board without raising or lowering the arm.

With the foregoing and related objects in view, the invention consists in the novel construction, combination and arrangement of parts hereinafter described and claimed.

In the accompanying drawings illustrating the invention,

Figure 1 is a top view of a well known form of typewriter having my invention applied thereto, the well known parts of the typewriter being shown by dotted lines, and 70 the parts of my invention shown by full lines.

Figure 2 is a front view thereof.

Figure 3 is a sectional detail on line 3—3 of Figure 2.

Figure 4 is a side view of parts shown in section in Figure 3.

The typewriting machine illustrated in the drawings is of the well known "Underwood" type; and, referring to the drawings, 2 designates the frame of the machine, 4 the key board, 5 the longitudinally movable carriage mounted on the frame, 6 the combined platen and paper-feed roller carried by the carriage and 7 the pivoted member or lever 80 which is manually operated to actuate the devices that turn or advance the roller 6 at the completion of the writing of each line. The carriage 5 is automatically moved forward or in the direction of the dotted line 90 arrow, step-by-step, during the writing operation and it is manually returned or moved in the reverse direction indicated by the full line arrow. The construction and operation of the parts thus referred to are 95 common and well known and no detailed description or illustration thereof is deemed necessary herein.

Secured at its respective ends to the bottoms of the side members of the machine 100 frame 2, is a plate or bracket 8, forming, in effect, a part of the said frame; and fulcrumed at 9 on the plate 8 is a lever 10 which extends forwardly and rearwardly from its fulcrum, and which is adapted to move horizontally beneath the key board 4. The forward end of the lever 10 is provided with a suitable handle 11 by means of which it may be manually moved across the front of the key board 4 from the left hand side of the 110 machine to or toward the right hand side thereof. The forward end portion of the

lever 10 moves beneath the plate or bracket 8 and it extends over a segmental bar or guard 12 which is secured at its respective ends to the bottom of the plate 8. The guard 12 is provided to resist any undue downward pressure upon the handle 11 or the forward end of the lever 10 during the manual operation thereof.

The rearward end portion of the lever 10 is connected to a small angle bracket 13 secured to the left hand end of the carriage 5, by a flexible member 14 which may be a cord, wire, chain or any equivalent thereof. The member 14 extends horizontally from the angle bracket 13 to and around a pulley 15 which turns on a horizontal axis in a bracket 16 secured to the upper portion of the right hand side of the machine frame 2. The member 14 extends downwardly from the pulley 15 to and around a pulley 17 which turns on a horizontal axis in a bracket 18 secured to the lower portion of the frame 2 beneath the bracket 16. The member 14 extends from the pulley 17 to and around a pulley 19 which turns on a vertical axis and which is carried by the rearward end of the lever 10 and terminates in a head 20 which is secured thereto. The head 20 is also secured to one end of a long helical spring 21 which extends therefrom to and around a pulley 22, carried by the forward end portion of the lever 10 and thence back toward the pulley 19 which has its other end secured at 23 to the lever 10.

The spring 21 forms, in effect, a continuation of the flexible member 14, and the spring 21 is adapted to draw the head 20 and therewith the end of the member 14 connected thereto toward the pulley 22 to take up the slack in the member 14 which otherwise would occur in the member, as will be hereinafter explained.

The head 20 is adapted to move back and forth between the pulleys 19 and 22, the head 20 being drawn by the member 14 toward the pulley 19 and by the spring 21 toward the pulley 22; and, when the head 20 is drawn by the member 14 to a position in close proximity to the pulley 19, the head 20 is adapted to engage a stop 24 which projects from the lever 10 and arrests the movement of the head 20.

The carriage 5 is shown in the central position; that is to say, about midway between the limits of its forward and reverse movements; and, in this position of the carriage 5, the head 20 is about midway of the ends of its path of travel between the pulleys 19 and 22. It will now be understood that if the carriage 5 be moved forward by the mechanism of the machine under the influence of the operation of the keys of the key board 4, the spring 21 will draw the head 20 toward the pulley 22 and thereby take up the slack in the member 14 occa-

sioned by the forward movement of the carriage 5. It will also be understood that if the forward end of the lever 10 be moved from the normal position shown in the drawings toward the right hand side of the machine, the rearward end portion thereof will move away from the pulley 17 and the head 20 will be drawn toward the pulley 19 until the head 20 engages the stop 24; and, during such movement of the head 20, the carriage 5 will be unaffected by the movement of the lever 10. After the engagement of the head 20 with the stop 24, the further movement of the forward end of the lever 10 toward the right causes the rearward end of the lever 10 to exert a pull upon the member 14 which moves the carriage 5 in the reverse direction. Thus the carriage 5 may be returned to the end of its reverse stroke or to any desired extent toward the same from any position of the carriage 5 between the limits of its forward and reverse movements, by moving the forward end of the lever 10 from its normal position toward the right to the extent that it is desired to move the carriage 5 in the reverse direction.

The spring 21 not only acts automatically to take up the slack in the member 14 but also, in so doing, it acts automatically to return the lever 10 to the normal position shown in the drawings, after the forward end thereof has been moved to any extent toward the right and released.

I shall now describe the mechanism for turning or advancing the paper-feed roller 6 during the reverse movement of the carriage 5 after the completion of each line of writing.

Secured to the upper portion of the right hand side of the frame 2 is an angle bar 26 which extends outwardly therefrom parallel to the path of movement of the carriage 5. The angle bar 26 has a longitudinal slot 27 formed therein for the reception of two screws 28 and 29 which penetrate the same and connect a plate 30 on one side of the bar 26 and a bracket 31 on the other side of the bar 26 in a manner to guide the plate 30 and bracket 31 and permit them to be adjusted longitudinally of the bar 26. The screw 28 is provided with a suitable head by means of which it may be turned, and it is adapted to serve as a clamping screw to draw the plate 30 and bracket 31 together and clamp the bar 26 between them to hold the bracket 31 in different positions of longitudinal adjustment on the bar 26. The bracket 31 is provided with a longitudinally extending arm 32 having a vertically arranged bearing-plate 33 formed on the free end thereof. Pivoted at 34 on the plate 33 is a stop 35 having a weighted lower end which maintains it normally in the vertical position shown in Figure 2.

The upper end of the stop 35 is provided

with a roller 36 arranged in the path of the forward arm 37 a lever 38 which is fulcrumed at 39 on a plate or bracket 40 on the carriage 5.

5 The rearward arm 41 of the lever 38 carries a roller 42 which is adapted to engage and move the member 7 when the lever arm 37 is moved in the direction of the arrow in Figure 1. The member 7 is connected to 10 and operates the usual devices for turning or advancing the paper-feed roller 6, and, when the lever arm 37 is moved in the direction of the arrow, the member 7 is moved by the lever arm 41 to turn or advance 15 roller 6 to the desired extent, after the completion of a line of writing. When the carriage 5 is moved in the reversed direction after the writing of a line, the lever arm 37 engages the stop roller 36 and is moved 20 thereby in the direction of the arrow shown in Figure 1 to operate the member 7 to advance the feed roller 6; and upon the next succeeding forward movement of the carriage 5 the lever arm 37 engages the stop 25 roller 36 and tilts the stop 34 to permit the roller 36 to pass beneath the lever arm 37 without affecting the lever 38. The stop 35 is prevented from tilting by the engagement of its side below its pivot 34 with the 30 end of the bracket arm 32, when the lever arm 37 engages the roller 36 during the reverse movement of the carriage 5. After the stop 35 is tilted by the lever arm 37 during the forward movement of the carriage 5, the stop 35 is returned to its normal or vertical position by its weighted 35 lower end.

After the member 7 has been moved to turn the paper-feed roller 6 as previously 40 described, it is automatically returned to its normal position shown in the drawings by the usual mechanism of the typewriter; and, when the member 7 is thus returned, it automatically returns the lever 38 to its 45 normal position, as shown in the drawings, following its movement therefrom by the engagement of its arm 37 with the stop roller 36, as previously described. Movement of the lever 38 by the stop roller 36 50 during the forward movement of the carriage 5 is prevented by the engagement of the lever roller 42 with the bracket 40.

It will now be apparent from the construction and operation of the mechanism, 55 as hereinbefore described, that it will be unnecessary for the operator to raise or lower his or her arm to either return the carriage 5 or to turn the paper-feed roller 6 after the writing of a line, and that these 60 operations may be accomplished by merely moving the hand horizontally across the front of the key board 4 in engagement with the handle 11 or end of the forward arm of the lever 10. After such movement of 65 the lever 10 to return the carriage 5 and

advance the paper-feed roller 6, the handle 11 or lever 10 is released and the spring 21 automatically returns it to the normal position shown in the drawing, as previously explained.

I claim as my invention—

1. In a typewriter the combination with its frame and its carriage movable in forward and reverse directions, of a hand operated lever fulcrumed on the frame and 75 movable to and from a normal position, a flexible member connecting the carriage and the lever and adapted to move the carriage in the reverse direction when the lever is moved from its normal position, said member 80 having a head thereon and said lever having a stop adapted to be engaged by said head to cause the carriage to be moved forwardly by the lever when it is moved from its normal position, a spring connecting 85 said head and said lever to draw the head away from the stop to take up the slack in said member, and means for guiding said member between the lever and the carriage.

2. In a typewriter the combination with its frame and its carriage movable in forward and reverse directions, of a hand operated lever fulcrumed on the frame and 95 movable to and from a normal position, a flexible member connecting the carriage and the lever and adapted to move the carriage in the reverse direction when the lever is moved from its normal position, said member 100 having a head thereon and said lever having a stop adapted to be engaged by said head to cause the carriage to be moved forwardly by the lever when it is moved from its normal position, means for guiding 105 said member between the lever and the carriage, said means including a pulley on said frame from and toward which said stop is moved when the lever is moved from and toward its normal position, and a spring connecting said head and said lever to draw 110 the head away from the stop to take up the slack in the member and to return the lever to normal position after being moved therefrom and released.

3. In a typewriter the combination with 115 its frame and its carriage movable in forward and reverse directions, of a hand operated lever fulcrumed on the frame and movable to and from a normal position and having a pulley mounted thereon, a flexible 120 member connecting the carriage and the lever and adapted to move the carriage in the reverse direction when the lever is moved from its normal position, a helical spring having one end thereof connected to 125 said head and extending therefrom around said pulley and back toward said head and having the other end thereof connected to said lever, said spring acting to draw the head away from the stop to take up the 130

slack in said member, and means for guiding said member between the lever and the carriage.

4. In a typewriter the combination with its frame and its carriage movable in forward and reverse directions, of a hand operated lever fulcrumed on the frame and movable to and from a normal position and having a pulley mounted thereon, a flexible member connecting the carriage and the lever and adapted to move the carriage in the reverse direction when the lever is moved from its normal position, means for guiding said member between the lever and the carriage, said means including a pulley on said frame from and toward which said stop is moved when the lever is moved from and toward its normal position, a helical spring having one end thereof connected to said head and extending therefrom around the pulley on the lever and back toward the head and having the other end thereof connected to the lever, said spring acting to draw the head away from the stop to take up the slack in the member and to return the lever to normal position after being moved therefrom and released, and means for guiding said member between the lever and the carriage.
5. In a typewriter the combination with its frame and its carriage movable in forward and reverse directions, of a lever fulcrumed on the frame and extending forwardly and rearwardly from its fulcrum and movable horizontally beneath the key board to and from a normal position and having a handle on its forward end, upper and lower guiding pulleys on said frame, a flexible member connected to the rearward end of the lever and extending therefrom

to and around the lower pulley, thence to and around the upper pulley and thence to said carriage and connected thereto, said lever operating said member to move the carriage in the reverse direction when the lever is moved from its normal position, and means automatically to return said lever to normal position after being moved therefrom and released and automatically to take up the slack in said member during the return of the lever to normal position.

6. In a typewriter the combination with its frame and its carriage movable in forward and reverse directions, of a lever fulcrumed on the frame and extending forwardly and rearwardly from its fulcrum and movable horizontally beneath the key board to and from a normal position and having a handle on its forward end, a flexible member connecting the carriage and the rearward end of the lever and adapted to move the carriage in the reverse direction when the lever is moved from its forward position, said member having a head thereon and said lever having a stop adapted to be engaged by said head to cause the carriage to be moved forwardly by the lever when it is moved from its normal position, and means for guiding said member between the lever and the carriage, said means including a pulley on said frame from and toward which said stop is moved from and toward its normal position, and a spring connecting said head and said lever to draw the head away from the stop to take up the slack in the member and to return the lever to normal position after being moved therefrom and released.

GEORGE F. SCHEFFER.
